UNITED STATES PATENT OFFICE.

JOHN PLATT AND WILLIAM RICHARDSON, OF OLDHAM, COUNTY OF LANCASTER, ENGLAND.

IMPROVEMENT IN MACHINERY FOR CLEANING WOOL.

Specification forming part of Letters Patent No. 36,727, dated October 21, 1862.

To all whom it may concern:

Be it known that we, JOHN PLATT, mechanical engineer, of Oldham, in the county of Lancaster, Great Britain, and WILLIAM RICHARDSON, mechanical engineer, of the same place, have invented Improvements in Machinery or Apparatus for Cleaning Wool and other Hairs of Animals from Burrs and other Extraneous Matters; and we do hereby declare that the following is a full and exact description thereof, reference being had to the accompanying drawings and to the letters of reference marked thereon.

In our arrangement of machinery or apparatus we employ a roller against which is placed a fixed blade, between which and a reciprocating blade the wool or other such material to be cleansed is introduced.

Another feature of our invention consists in the adaptation of mechanism to the above-described machinery for opening out the material previously to its being presented to the rollers and blades. For this purpose we adapt spiked rollers or other such opening or carding apparatus, working in a dish, and we employ a transferring-comb in conjunction with the said spiked roller and fixed spikes, which draws off the material in detached tufts and presents it to the said roller and blades. These constitute the main features of our invention, which we claim to be our invention, and desire to secure by Letters Patent, and we will now proceed to describe how the same may be carried into practical operation, reference being had to the accompanying drawings, in which—

Figure 1 is a longitudinal section of the machine; Fig. 2, a plan or top view, and Fig. 3 a detached plan view of certain of the parts.

The frame-work of the machine is at *a*, upon which are mounted two rollers, *b b**, carrying an endless apron, formed of transverse strips of wood *c*, adapted to leather or other bands. A few only of these strips are shown in the drawings, their continuation being denoted by dotted lines. At the inward end of the endless apron is a fluted roller, *d*, and beyond this a roller, *e*, provided with a number of spikes. This roller is situate above a dish, *g*, and below a shield, *f*, and extending downward from the former is a plate, *h*, the inward extremity of which at *i* is formed as a grating.

At *k* is a revolving roller, covered with leather or other such material, against the periphery of which is placed a blade, *l*, carried by a transverse rail, *m*, and pressed against the roller by a spring, *n*. The reciprocating blade is at *o* mounted upon a center-pin which is carried by rods *p*, connected at their lower ends to cranks *8*, formed upon a shaft, *r*. (See the detached plan view, Fig. 3.) The blade *o* is also carried by levers *s*, which are jointed to centers at *t*, and which therefore guide the blade so as to cause it to scrape lightly against the periphery of the roller *k*, when it is moved upward by the cranks *8*, the rod *p* turning upon the center *u*.

Upon the shaft *r* is a pinion, *v*, taking into another, *w*, upon a shaft, *x*. The latter pinion carries a crank-pin, *y*, to which is adapted a connecting-rod, *z*. This rod (see the detached Fig. 4) is formed in two parts, and the lower, *1*, is constructed as a cylinder, within which the upper part, *2*, is capable of sliding but the two portions are kept apart by means of a spring, *3*. A vibratory motion may therefore be communicated by the crank *y* to the lever *4*; but in case of any obstruction arising the said spring will collapse, so as to produce a modified motion only. The lever *4* is fixed to a shaft, *6*, to which is adapted a series of prongs or combs, *7*, caused, therefore, to vibrate, so as to pass through the teeth of the roller *c* and through the teeth of a row of fixed prongs, *9**, downward along the plate and grating *h i*, and to approach the periphery of the roller *k* between the fixed blade *l* and vibrating blade *o*.

Upon the shaft *r* is a second pair of cranks, *9*, which operate by means of connecting-rods *19* upon bell-crank levers *10*, turning upon a center at *11*. The vertical parts of these bell-crank levers carry a plate, *12*, which, being thus caused to vibrate, scrapes lightly against the periphery of the roller *k*.

At *13 14* are partitions constituting shields and extending from one side framing to the other. The roller *k* is indented upon its surface with right-and-left-handed spiral grooves, which therefore cross each other, as shown in the detached view of the said roller at Fig. 5.

Having pointed out the general arrangement and construction of the machine, we will proceed to explain how the several moving

parts may be driven. The fast and loose pulleys for communicating the motive power are at 15, adapted to the shaft *r*, and the cranks 8 9 9 are therefore driven direct. Upon the shaft *r* is a pinion, *v*, taking into another, *w*, upon a shaft, *x*, and the said pinion, *w*, carries the crank-pin *y*, to which the rod *z* is connected, and thus the vibratory motion is communicated to the lever 4 and comb 7. Upon the shaft *x* is a pulley, 16, over which a band passes and from thence to another pulley, 17, upon the shaft 18 of the roller *k*. This shaft 18 carries a pulley, 19, which communicates motion by means of a pulley, 20, to a shaft, 21, and upon this is a toothed wheel, 22, gearing into another, 25, upon the axis of the spiked roller *e*, and from thence motion is communicated to the roller *b** of the feed-apron by the pinion 23, and to the fluted roller *d* by the pinion 24.

The operation of the machine is as follows: The wool or other such material to be cleaned is placed upon the apron *c*, which carries it forward beneath the roller *d* and delivers it to the spiked roller *e*, which, by revolving in the direction of the arrow, opens it out from its entangled mass. The comb 7, being caused, as before described, to vibrate, removes the material from the teeth of the spiked roller *e* and through the prongs 9* in detached tufts along the plate *h* and presents them to the surface of the roller *k*, which, by conveying them upward, presents them to the edge of the blade *l*, where the burrs or other extraneous matters are loosened. Here they are acted

upon by the vibrating blade *o* thrusting them against the said fixed blade *l*, which operation causes the burrs and other extraneous matters to be separated and fall downward through the grating *i*, while the cleaned wool or other such material is carried upward between the roller *k* and blade *l*, the grooves upon the surface of the said roller assisting their passage. A portion of the wool will fall from the roller and the remainder is detached and caused also to fall by the scraping action of the vibrating blade 12. The use of the elastic rod formed by the spring 3 will now be perceived, for, should the transferring-comb remove an unusual quantity of material, an obstruction would be caused to its full vibration, and a derangement of the parts would follow if the said rod were rigid.

Having thus described our invention, we claim as new, and desire to secure by Letters Patent—

The combination of the spiked roller *e*, vibrating comb 6 7, toothed plate *h* *i*, roller *k*, breast *l*, vibrating blades *o* 12, bell-crank levers 10, and connecting-rods *z* *p* 9, all constructed, arranged, and operating substantially as and for the purposes shown and explained.

Patent Office, 14 St. Ann's Square, Manchester.
